UNITED STATES PATENT OFFICE.

JAMES T. MATHIS AND GEORGE W. HARRISON, OF KOSCIUSKO, MISS.

IMPROVEMENT IN PLOWS.

Specification forming part of Letters Patent No. 105,103, dated July 5, 1870.

To all whom it may concern:

Be it known that we, JAMES T. MATHIS and GEORGE W. HARRISON, of Kosciusko, in the county of Attala and State of Mississippi, have invented certain new and useful Improvements in Plows; and we hereby declare the following to be a full, clear, and exact description thereof, reference being had to the accompanying drawings, forming part of this specification, in which—

Figure 1 is a perspective view, and Fig. 2 a side elevation.

These improvements relate to the general construction and arrangement of the parts of a plow.

In the accompanying drawings, A represents the beam; B, the handles; C, the connecting cross-bar; D, the subsoiler-standard, situated at the rear end of the beam, and attached at its upper end to the cross-bar C.

D' is a diagonal brace reaching from the subsoiler-standard to the beam, and secured by a nut on its rear end.

E represents the subsoiler, attached to the lower end of the standard D by a bolt, d.

The upper part of the subsoiler has a vertical slot, d', by means of which it is made adjustable to the proper height.

e represents a lug inserted in the standard D and situated in the slot, and intended as a guide to the subsoiler and to prevent lateral movement thereof.

F is the plowshare, the landside f of which is bifurcated at its upper part, and one of the arms, f, thereby formed attached as a shank to the beam A, while the other, f', is curved, as seen in the drawings, and secured by a bolt to the standard D.

G is the colter, properly attached to the beam, and situated before the share.

It should be observed that the subsoiler may be taken off by removing the bolt d, and any kind of a plowshare substituted.

Having fully described our invention, what we claim as new, and desire to secure by Letters Patent, is—

The combination and arrangement of the standard D, subsoiler E, with slot d' and bolt d, brace D', and arm f, as described.

J. T. MATHIS.
G. W. HARRISON.
